UNITED STATES PATENT OFFICE

HENRY L. PITMAN OF WESTFIELD, NEW JERSEY, ASSIGNEE, BY MESNE ASSIGNMENTS,
TO ELLIOTT-FISHER COMPANY, A CORPORATION OF DELAWARE

COMBINED TYPEWRITING AND COMPUTING MACHINE

Application filed January 19, 1926. Serial No. 82,226.

This invention relates to combined typewriting and computing machines of the well-known Underwood-Hanson type, in which computing wheels are actuated by toothed-racks formed upon pin-bars having digit index-pins. The lower ends of said index-pins are normally flush with the lower edges of the pin-bars. By means of interposed, and related mechanisms said index-pins may, 5 by operation of the numeral typewriter keys, be set so that their lower ends extend below the lower edges of the pin-bars. Each pin-bar has nine index-pins corresponding to the significant numerals, and the spacing between the pins along the bar corresponds to the distance the rack must move to rotate a computing wheel from digit to digit.

A bar or general operator, transversely disposed relatively to and immediately below said pin-bars, is given a reciprocating movement after the index-pins have been set. In its forward movement, said bar, by means of the index-pins set in its path, moves the pin-bars forwardly, causing rotation of 20 the computing wheels through a number of digit spaces corresponding to the index-pins which were set. The return movement of the general operator restores the rack-bars without reversing the computing wheels. 25 Said wheels during this return movement are actuated by the usual carry-over mechanism, which becomes active during said return movement.

One of the features of this invention is the 30 provision of improved means and a simple arrangement thereof, whereby the setting of any index-pin positively restores any other index-pin which has been previously set in the same pin-bar.

In said arrangement, the index-pins are 35 square or rectangular in section, and are retained in vertical slots formed in a block fastened to the side of the pin-bar. Interposed between the block and pin-bar is a thin stamping of resilient material, having 40 prongs with nodules formed on the ends thereof, said nodules serving as detents which co-act with suitable notches in the sides of the index-pin to hold said pins in either normal or depressed position. The

partitions formed between the vertical slots of the blocks in which the index-pins are retained, have notches which, with similar notches in the sides of the index-pins, form a depression or channel which is terminated at each end by the outer sides of the slots in which the end pins are retained. Nested in said channel is a group of blocks, each having an upper surface shaped into an obtuse wedge. The sides of these wedges contact with the upper edges or shoulders of the notches in the sides of the index-pins. The blocks are proportioned so that when placed end to end they occupy the length of the channel, in which they are nested to such an extent that only one pin can be fully depressed and entered between the blocks. Thus, every time a pin is depressed and entered between the blocks, some of the blocks are displaced along their channel. Conversely this displacement of said blocks causes the extrusion and positive restoration of a previously-depressed pin in the same bar.

One advantage gained by this invention is 55 that it affords a flexible index-setting device without the use of the springs and latch-bar usually employed in previous inventions. Examples of such previous inventions are shown in the patent to E. Thomas, No. 1,287,517, dated December 10, 1918, and the 60 patent to H. Hanson, No. 1,291,859, dated January 21, 1919.

Another feature of the present invention is that by means of the positive displacement of the aforesaid blocks, any pin previously set is positively restored by the setting of another pin in the same pin-bar. This feature is of particular advantage in combined typewriting and computing machines in which computations are made subtractively as well as additively. Such a machine is illustrated in the patent to O. Minton, No. 1,280,065, dated September 24, 1918, in which subtraction is effected by a complementary addition of the number to be subtracted. Said machine is set for subtraction by manually pressing a subtraction key, or the setting for subtraction may be automatically effected by the letter-feed carriage as it moves into a subtraction zone. When the machine is thus

set for subtraction, either manually or automatically, the digit "9" pin in each bar is set by means of suitable devices to be described later. In the present invention said devices 5 include a bail actuated by the usual subtraction-setting devices, said bail acting directly upon each "9" pin to set it. Said bail is also extended to reach a "9" pin in a pin-bar that has been advanced by the denomination-selecting means. The pin for the digit "9" must be set in each bar, because it is a necessary condition in complementary subtraction that all the bars in which no number is indexed by operation of a numeral-key shall 10 add "9". In each pin-bar wherein a significant number to be subtracted is indexed, the "9" pin is restored. By means of the present invention, this restoration is effected positively without the use of devices previously 15 employed, such as a small lever mounted beside each "9" index-pin and means for actuating said levers to restore the "9" index-pin when another index-pin is set. In this invention said small levers and actuating means 20 are not necessary.

Another advantage gained by this invention is a reduced liability of errors in the computations effected by the machine. As is well known a flexible pin-bar is useful in 25 enabling the operative to easily correct an error made in writing a number. Before the number is registered in the totalizer, the operative may correct the error by back-spacing the typewriter-carriage to the place 30 where the wrong digit was printed, erasing said digit and writing the correct one in its place. By means of this invention the pin corresponding to the wrong digit is positively restored when the correct digit is printed, 35 and its corresponding pin set. There is no liability of an error on account of a restoring spring being sluggish or slight binding of the index-pin in its cage, because, in this invention, no restoring springs are used, and a 40 slight binding of the index-pin in its cage would not matter, as the pin is positively restored.

In machines of the type herein shown and 45 illustrated, the pins are set by means of pin-setting bars, of which there is one for each digit. In the present invention "0" has a corresponding pin in each pin-bar. The "0" pins are not reached by the cross-bar on the general operator and are, therefore, ineffective to rotate the computing wheels. They 50 are provided for the purpose of restoring pins that were indexed through operation of the wrong numeral-keys. Other functions of said pins will be described further on. A 55 "0" pin-setting bar is also provided. Said pin-setting bars are arranged over and between transverse rows of pins. A pin-bar in which a pin is to be set is pushed forward by the usual denomination-selecting means 60 65 actuated by the letter-feed carriage, so that

the pins in said bar are directly below their respective pin-setting bars.

The pin-setting bars with their usual parallel motion linkages, rock-shafts, and subtraction-setting devices are built up into the usual frame-like structure. This structure is substantially simplified in this invention, because it does not embody the elements formerly necessary for positively restoring the "9" pins in subtraction.

In this invention the "0" pin is used to restore any other pin after the digit indexed by said other pin has been registered in the totalizer during a forward movement of the pin-bar. This restoration takes place when said pin-bar is almost at the end of its return movement. To this end there is provided on the pin-bar and adjacent to the "0" pin a small lever of the first order. One end of this lever engages the "0" pin by means of a notch in said "0" pin. The other end of the lever is engaged by a bail which extends across and under all the pin-bars and "0" pin-levers. By means of a suitable connection this bail-bar is actuated by the general operator when the pin-bars are almost fully restored, causing said bail-bar to rise, engage and actuate the "0" pin-levers, thereby causing all the "0" pins to be depressed and consequently causing all other pins that were set to be restored. The "0" pin is normally in a depressed position when no other pin in the bar is set.

Other features and advantages will hereinafter appear.

In the accompanying drawings,

Figure 1 is a sectional side elevation of an Underwood-Hanson combined typewriting and computing machine, showing only such parts as are necessary to illustrate this invention.

Figure 2 is a perspective view of the pin-bars and the means for restoring, after computation is effected, the pins that were set. This figure also shows means actuated by an elimination key for restoring pins that were set.

Figure 6 is a diagrammatic plan view of the pin-setting bar arrangement.

Figure 7 is an operated side view, showing the pin-bar as moved by the general operator.

Figure 8 is an operated side view, showing the pin-bar in a position where the index-pin has just been restored.

Figure 9 is a detailed side view of the index-pins and related parts in normal position.

Figure 10 is a side view of the index-pins and related parts, and shows one of the pins depressed.

Figure 11 is a diagrammatic view of the index-pins and inter-acting elements, and shows said pins in normal positions.

Figure 12 is a diagrammatic view of the index-pins and inter-acting elements, and shows one of said pins depressed.

Alphabet keys 10 and numeral-keys 11 mounted upon the forward ends of levers 12 are operated to rock bell-cranks 13, which swing type-bars 14 upwardly and rearwardly causing type 16 to print against the platen 17. The platen is revolubly mounted in a carriage 18, which is propelled by a spring-barrel (not shown) and controlled in the usual manner by escapement-wheel 19 and dogs 20, the latter being operated by a universal-bar 21, which is actuated by heels 22 on the type-bars. Connection between the escapement-mechanism and typewriter-carriage is effected by means of a rack 23 swung upon arms 24 from the typewriter-carriage. Said rack meshes with a pinion 25 connected to the escapement-wheel. Computing wheels 26 have a forward driving ratchet connection (not shown) to pinions 27, which mesh with racks 28 formed upon pin-bars 29, there being one pin-bar for each computing wheel. Each bar carries a set of index-pins 30 which are depressible by means of linkages 31, the latter including pin-setting bars 32 and rock-shafts 33 which have the usual arms 34 engageable by stems 35 pendent from the numeral-keys 11. Depression of any numeral-key 11 to operate its type-bar causes the depression of a corresponding pin-setting bar 32, whereby one of the index-pins 30 is depressed in the path of a bar 36 on a general operator 37, which may be operated by a crank 38 after all the desired index-pins 30 have been set. The crank is fixed upon a rock-shaft 39, which carries a segmental gear 40 on each end, meshing with an idle pinion 41, the latter meshing with a rack 42 on each side of the machine. Said racks form part of the general operator 37.

In order to depress one of the index-pins 30, the pin-bar in which it is mounted must be pushed forward so that said index-pins come under the pin-setting bars 32. This is done by means of the usual denomination-selecting mechanism which is controlled by the letter-feeding movements of the typewriter-carriage through a computing zone. Said mechanism includes a dog 45 mounted on the typewriter-carriage, and which, during letter-feeding movements of the carriage is effective to actuate denomination-selecting jacks 46, one after the other. Said denomination-selecting jacks when thus actuated depress thrust rods 47 whose lower ends are pivoted to levers 48, which operate linkages 49 to push the pin-bars forward by means

of bell-cranks 50. Said linkages form a transposition device, whereby the order in which the pin-bars are selected is reversed from the order of operation of the jacks. Thus, by means of this transposition device, the extreme right-hand jack 46 causes the extreme left-hand pin-bar 29 to be selected, the other jacks and pin-bars being operated in following order. The usual Underwood denominational tabulating means are provided and include a set of denominational tabulating keys 53, which operate by the usual means (not shown) plungers 54, causing said plungers to rise in the path of counter-stops 55 suitably mounted on the typewriter-carriage. When any of the tabulating keys are operated the rack 23, by means of connections (not shown), is disengaged from the escapement-pinion 25, and the carriage moves forward under the influence of its propelling spring until the counter-stop 55 strikes the plunger 54 which is raised in its path.

The index-pins are arranged upon the pin-bar 29 in a pin-block 58 having slots 59 formed therein, in which said index-pins may slide up and down. The lower ends of these pins are substantially flush with the bottom surface of said pin-block when said pins are in their upper or normal position. In each pin-bar there are nine index-pins, one for each digit, from "1 to 9," inclusive, and a "0" pin 60. As will be shown, said "0" pin is normally down when no other pin in the bar is set. Each pin has formed in the side thereof a slot 61. A longitudinal cut in the side of the pin-block 58 forms therein the slots 62. Said slots 62 in the pin-block and slots 61 in the index-pins form a channel 63, within which are placed, end to end, hardened steel blocks 64, each having upper surfaces 65 formed into an obtuse wedge, the sides of which are equally inclined toward the horizontal. Said blocks may have holes 64^a to make them lighter and are proportioned, so that, when placed end to end, they occupy the channel to an extent that will leave a gap 66, see Figures 11 and 12. The blocks 64 have a sliding fit in the slots 62, are partially supported by the pins, and may be displaced so that the gap 66 may be opened between any two blocks or between either of the end blocks and adjacent channel terminating wall 67 formed by the outer side of each end pin-slot. Thus, wherever a pin is depressed this gap is opened under the pin and closed by the pin as the pin displaces its adjacent block. The displacement is effected by the camming action of the shoulder 69 upon the adjacent wedge surface of the adjacent block, to spread the blocks a pre-determined limit, when two adjacent blocks co-operate to arrest the pin.

Conversely, if a pin when depressed displaces a block, said block may, by displace-

ment thereof in the opposite direction, cause the restoration of said pin. This displacement of the block in the opposite direction, and the consequent restoration of the pin, are effected when another pin is depressed, and pushes said block aside either by acting on it directly, if the two pins are adjacent, or by means of intermediate blocks, if the pins are not adjacent. The latter condition is illustrated in Figure 12, where the depression of the "5" pin, for example, has caused the restoration of the "0" pin by displacing the blocks, intermediate of said "5" pin and "0" pin, toward the left. If, for example, the "4" pin is then depressed, it would cause the restoration of the "5" pin by displacing the block, between said "4" pin and "5" pin, toward the right. The gap 66 is proportioned so that only one pin at a time can be fully depressed.

The index-pins are detained in either upper or lower position by means of a simple device consisting of a thin stamping 72, of resilient material, having prongs 73 formed thereon. Said prongs are given an initial set so that nodules 74 formed on the ends thereof are pressed against and detain the index-pins in either upper or lower position by means of slots 75 and 76 formed in the sides of said index-pins, see Figure 4. The stamping 72 is placed between the pin-block 58 and pin-bar 29. Tongues 77, formed between the prongs 73, cover the slots 59 in the pin-block and retain the blocks 64. The ends of said tongues bear upon the partitions formed between the pin-slots 59. The upper web 78 of the stamping retains the upper part of the index-pins and the upper tips of the blocks 64. The assembly of the indexing elements is secured by means of screws 79, threaded into the pin-block after passing through holes 80 in the pin-bar 29 and the stamping 72. The pin-bar 29 is suitably recessed at 81, see Figure 4, to provide clearance for the prongs 73 when they bend outward as an index-pin is actuated.

The feature of positively restoring one index-pin when another one is depressed makes it possible to simplify some of the elements necessary for subtractive computation. The usual means for subtraction include the subtraction-setting key 82, connected by a link 83 to an arm 84 keyed to a shaft 85. Said shaft has also keyed to it a latch 86, see Figure 3, which holds in normal forward position a subtraction bar 87 against the tension of a spring 88. In Figure 3, the subtraction key (not shown) has been pressed in, causing the latch 86 to be withdrawn from the subtraction bar 87, which, thus released, is pulled rearwardly by the spring 88. The latch 86 may also be withdrawn by the usual means (not shown) which are automatically operated by the movement of the letter-feed carriage into a subtraction zone. The rearward movement of this subtraction bar causes

a bail 89, extending across all the pin-bars, to set each "9" pin in said pin-bars. Said bail has an extended ledge 89^a to reach the "9" pin in a bar that may have been advanced by the denomination-selecting means. Said bail is operated by the usual means including a blank 91 fastened to a bail-shaft 92 to which the bail is keyed. Said bail-shaft may be pivotally supported upon the pin-setting frame 93. The blank 91, as the subtraction bar moves rearwardly, is engaged by a spring-pressed hook-shaped member 94 pivoted to the subtraction bar, causing the bail-shaft to rotate. Said bail is thereby depressed and sets the 9 index-pins 30 as the subtraction bar moves rearwardly. Toward the end of the rearward subtraction bar movement, said hook-shaped member is withdrawn from the blank when an extension 95 thereon is arrested by the abutment 96. The withdrawal is effected by thus causing the hook-shaped member to slightly rotate about its pivot 97. A spring (not shown) then retracts the bail. The cross-bar 36 restores the subtraction bar by means of a shoulder 87^a on said subtraction bar, and a spring 98 forces the latch 86 into the notch 98^a.

Heretofore, a small lever of the first order was pivoted on the side of each pin-bar, and one end thereof engaged the "9" pin. The other end of said lever was raised when the "9" pin was set through pressing the subtraction key. By means of a bar similar to bars 32 and having corresponding linkage, which was connected during subtraction to each rock-shaft 33, except the ninth, said other end of the lever was depressed when a digit to be subtracted was indexed. In this manner the 9 pin was positively restored. Because the 9 pins are positively restored by means of the blocks 64, such means are not necessary in this invention, and the elimination thereof results in a simplified pin-setting frame arrangement which also includes elements for indexing a "0" pin. A plan view of said arrangement is shown in Figure 6. As the machine is set for subtraction all the rock-shafts are shifted by sliding them forwardly, by the usual means which include a swingable transverse-bar 99 pivoted at 100 and engaging the rock-shafts 33, by means of slots 101 therein. Said bar is connected to the subtraction bar by means of the usual connection including a bell-crank-lever 102. As the subtraction bar moves rearwardly, said transverse bar is caused to rotate slightly in a clockwise direction, thereby shifting all the shafts forwardly so that complementary setting bars are engaged, subtractive computation being effected in the Underwood-Hanson machine by the well-known method of adding complements of the numbers to be subtracted. In the unit wheel, or last column to the right, an extra "1" is added by the usual means which are not shown in the drawings, and 130

have been omitted for the sake of clearness, but which are effective during subtraction.

The numbers indexed in the pin-bars are additively or subtractively registered in the computing wheels 26, by giving the general operator 37, which includes the transverse bar 36, a single reciprocating forward and rearward movement. Said bar in its forward movement encounters the lower ends of the index-pins projecting below the pin-bars, thereby causing said pin-bars to move forward and rotate the computing wheels. In its return or rearward movement, said transverse bar engages shoulders 103, formed on the pin-bars and returns said pin-bars without reversing the computing wheels in the well-known manner shown and described in the patent to H. Hanson, dated September 24, 1918, No. 1,279,688.

20 During this return movement, the usual carry-over-mechanism 104, which has a one-way drive through the pinion 105 becomes effective. During said return movement, the index-pins are re-set. To accomplish the re-setting of the index-pins, there is provided a cross-shaft 106, pivoted in the side frames 107 of the computing section. Said shaft has keyed thereon a bail 108 having a broad upper surface 109. By means of an arm 110 keyed to said shaft, and a lever 111 having a pin 112 in one end thereof, said lever being pivoted upon the left-hand side frame of the computing section, said shaft may be slightly rotated clockwise. This occurs during the return movement of the general operator, when the usual spring-pulled one-way cam-pawl 113, pivoted on the general operator, encounters and engages the edge 114 formed at the end of said lever, causing said lever to rotate until the tip 115 thereof may escape from said cam-pawl, as shown in Figure 8. The rotation of the shaft 106 causes the bail surface 109 to be raised and presented against rounded ends 117 of levers 118 pivoted on each pin-bar at 119. Each of said levers is rotated thereby, and the "0" pin 60, with which each lever is articulated by means of a slot 120 in the side of said pin, is depressed. By the depression of the "0" pins in this manner, just before the pin-bars are returned, all the index-pins which were set and restored, and a new number may be indexed in the pin-bars. By means of a flange 121 on its pivot stud, see Figure 5, each of said levers 118 is spaced from its pin-bar so as to clear the stamping 72. A clearance 127 is also formed on the pin-block 58 for said lever.

60 All the index-pins may be restored in case of error by pressing an elimination key 122. Said elimination key, connected by a link 123 to an arm 124 fastened to the shaft 106, may cause said shaft to rotate and restore the pins in the manner just described.

65 A torsion spring 125 is provided to restore the bail after said bail has restored the "0"

pins. Said spring, as shown in Figure 2, is applied at one end of the shaft 106 to rotate said shaft in a counter-clockwise direction. Said rotation is limited by a pin 126 driven into the left side frame of the computing section, said pin stopping the lever 111 with which the arm 110 in the shaft co-acts.

Variations may be resorted to within the scope of the invention, and portions of the improvements may be used without others.

Having thus described my invention, I claim:

1. In a computing machine having a denominational series of bars, pins settable in said bars, pin-setting members adjacent said bars for setting said pins, and numeral-keys for operating said members; means co-acting with said pins in each pin-bar and including a cam-faced movable element between each two adjacent pins in said bar, whereby the depression of a pin displaces one or more of said elements and thereby causes the extrusion and positive restoration of a previously-set pin in the same bar.

2. In a computing machine having numeral-keys ranging from "0" to "9", pin-setting members operable by said keys, and bars arranged in denominational series and each having a pin settable by one of said members; means including separate movable elements co-acting with said pins, whereby the depression of a pin displaces one or more of said elements and thereby causes the extrusion and positive restoration of any other pin previously set in the same bar.

3. In a computing machine, the combination with an indexing pin-bar having settable pins slidable in transverse channels in said bar, of a longitudinal channel intersecting said transverse channels and formed by slotting said pins and the partitions formed between said transverse channels, and movable elements assembled within said longitudinal channel and so proportioned that when placed end to end they occupy all of said longitudinal channel less a predetermined working gap, said movable elements being operative by the full depression of one of said pins to displace said elements by filling the gap, and operable by the depression of a second pin to cause the extrusion and positive restoration of the first pin.

4. The combination of numeral-keys, rows of index-pins settable by said keys, and a confined row of movable elements for each row effective to prevent simultaneous setting of two index-pins in any row, each element having beveled shoulders to enable it to be cammed in opposite directions by the adjacent index-pins, for restoring the previously-set index-pin.

5. The combination of numeral-keys, rows of index-pins settable by said keys, and confined rows of movable elements effective to prevent simultaneous setting of two index-

- pins in any row, each element having beveled shoulders to enable it to be cammed in opposite directions by the index-pins, for restoring the previously-set adjacent pin, and means in which the pins and elements are mounted, said mounting means having rows of vertical guiding slots for said pins, said guiding slots supporting the index-pins for the camming actions upon said elements, and 10 said mounting means formed with supporting means upon which the movable elements rest while being cammed.
6. An indexing mechanism for computing machines, including rows of index-pins, each 15 row including nine digit-pins, keys for setting said pins, means for detaining any set pin, and means for enabling the power of any of said keys to be utilized to force back to normal position any pre-set pin.
7. In a computing machine having dials and a set of bars, each provided with settable index-pins for driving the dials, and a general operator to engage said pins; means operative to restore a wrongly-set pin by the 20 subsequent setting of a correct pin, said restoring means including a train of separable elements slidably displaceable upon said pin-bar, said bar having a grooved portion along which said elements may slide, said elements 25 movable in said groove by means of the index-pins, and effective to prevent simultaneous depression of two pins, and to restore any 30 previously set pin.
8. In a computing machine, the combination of a computing bar having a series of index-pins key-settable therein, and a train 35 of separable elements assembled end to end within a groove cut along said bar and cut crosswise through said index-pins, the setting 40 of any index-pin displacing one or more of said elements along the groove to block the simultaneous setting of another index-pin.
9. In a computing machine having a movable pin-bar and a series of key-settable indexing pins, the combination of means operative to eliminate an incorrectly-set pin by the subsequent setting of a correct pin, said 45 means including a groove in said pin-bar, and a series of separable wedge-shaped elements slidably displaceable along said groove in the pin-bar to block the depression of all the pins by their endwise displacement by one pin, said wedge-shaped elements being operative to forcibly restore a depressed 50 pin when a second pin is depressed.
10. In a computing machine, the combination with a computing bar having a series of key-settable indexing pins, of self-correcting means effective to restore a misset 55 indexed pin by a subsequent key-set pin, said means including a groove formed longitudinally of said bar and across each indexing pin, and a separable cam for each indexing pin assembled as a series within said 60 groove, each cam displaceable by any indexing pin and each cam engageable with an indexed pin to restore said indexed pin through the redisplacement of the series of cams by any pin subsequently set by a key. 70
11. In a computing machine, a computing bar having key-settable pins therein, and having a continuous longitudinal groove, said groove continuing through each settable pin, and a train of separable elements assembled 75 end to end within said composite groove, one element for each pin, said train of elements being displaceable by the indexing of any pin to prevent the simultaneous setting of two pins in the bar, and to restore a pin 80 previously set by mistake.
12. In a computing machine having a bar and a series of key-depressible indexing pins, the combination of a continuous groove through both pin-bar and pins, a train of 85 separable elements mounted within said groove, and movable as a series by the depression of a pin and operable through their form and location to prevent the depression of a second pin without restoring the first 90 pin depressed.
13. In a computing machine, a self-correcting indexing mechanism including a computing bar having a groove longitudinally thereof, a series of key-set index-pins settable 95 crosswise of said bar, each index-pin having a groove alignable with said groove in said bar, and a series of separable elements, one element for each index-pin, said elements assembled as a connectible series within the 100 groove formed in said bar and index-pins, each element so formed that the displacement thereof within said groove by the setting of one index-pin will forcibly re-displace said series of elements and effect the restoration 105 of the first key-set index-pin.
14. In a computing machine, the combination of a bar movable to compute and a unit of key-settable index-pins secured to the side of said bar and operative to predetermine the 110 extent of movement for said bar in computing, said unit including a detached housing having a series of transverse open grooves, the index-pins being slidable within said 115 grooves and flush with the face of said housing, a groove being cut longitudinally of said housing and transversely through said index-pins, and a series of separable elements arranged within said longitudinal groove and each element having a formation effective to 120 displace the other elements and limit the setting of the index-pins by the keys.
15. In a computing machine having computing devices including a denominational bar having a series of key-set indexing pins, 125 the combination of a series of pin-restoring elements on the pin-bar including a groove along said pin-bar and across all of said pins, separable blocks, one block for each pin and the series of blocks movable along said 130

groove, each block formed with cam-faces engageable by two adjoining pins, means formed by the groove in each pin to engage with and displace one or more of said blocks along said groove in the pin-bar, and stop-means formed by the groove in said pin-bar and operable to limit the extent of longitudinal displacement for said blocks as a series in two directions to limit the full depression of one pin and prevent the depression of any other pin without simultaneously restoring the first pin depressed.

16. In a computing machine having a pin-bar and a series of key-depressible indexing pins, the combination of a groove through both bar and its pins, a train of separable elements mounted within said groove to slide as a series through the groove in the series of index-pins by the depression of a pin, and end stops formed in the bar to limit the sliding movement of the separable elements, said elements as a train having an endwise lost motion of predetermined extent between said 25 stops and an endwise abutment as a series to provide a working gap between sections of said elements whereby any pin when depressed closes up the gap, and wedges between the divided train, said wedged-in pin preventing the simultaneous depression of another pin.

17. In a computing machine, a row of settable index-pins and, means to enable any pin to restore any previously set pin, including a row of co-operative pin-restoring elements having a longitudinal movement and having wedging sections engageable by said row of index-pins, each index-pin insertible between the wedge-sections to effect endwise 40 displacement of said pin-restoring elements, and said wedge-sections being effective upon the other index-pins to restore any index-pin set by mistake.

HENRY L. PITMAN.
